TAPE DISPENSER

Edwin W. Mason, Wyckoff, N. J.

Application May 25, 1946, Serial No. 672,191

1 Claim. (Cl. 164—84.5)

1

The invention relates to a device for dispensing adhesive tape of the pressure-sensitive type.

More particularly, the invention relates to a novel construction of cutting unit for such a dispenser for severing any desired length of the tape from the roll contained in the dispenser.

An object of the invention is to provide such tape severing means which will permit the efficient and accurate severance of any desired length of the tape from the roll and will maintain the free end of the remaining portion of the tape in position for ready grasping and thereafter unwinding from the roll of an additional length of tape which is to be dispensed.

In accordance with my invention I provide, in a dispenser for adhesive tape of the pressure-sensitive type, a stationary knife, preferably having a serrated cutting edge, which knife is fixed to a standard positioned in advance of the roll of tape retained within the dispenser, and a movable support for the tape immediately rearwardly of the cutting edge of the knife, which movable support is depressible when the tape is being severed, the movement of the tape support being induced along a cam surface and which movement will cause a slight flexing of the knife as the tape is severed by its cutting edge.

Specifically, my novel construction resides in the provision of a standard, integral with the frame or body of the dispenser, which standard has a cam surface at its upper extremity along which cam surface is adapted to ride a supporting member for the length of tape immediately rearwardly of the length being severed by the knife. The portion of the tape which is being severed is thus permitted to be depressed to a sufficient extent to permit efficient and accurate severance of any desired length of the tape. The movable surface upon which the tape is supported rides up on the cam surface to a sufficient extent to leave the leading edge of the successive length of tape in position for ready grasping for the subsequent movement forwardly of another desired length of tape over the cutting edge of the knife.

The advantages of my novel construction will be apparent to those skilled in the art from the specific embodiment thereof illustrated in the accompanying drawings, in which Fig. 1 is a front elevation of a tape dispenser constructed in accordance with my invention; Fig. 2 is a side elevation thereof; Fig. 3 is an enlarged detail front view of the spring knife mechanism and movable tape support; Fig. 4 is a section on the line 4—4 of Fig. 3; and Fig. 5 is an enlarged top view of the spring knife mechanism and movable tape support.

Referring more particularly to the drawing, 6 designates the dispenser body, of preferably cast metal construction, having a base 7 of rubber, felt, or other material having a surface-gripping

2

characteristic, which body may take any conventional form, not particularly the quasi-pyramidal outline illustrated, but which has an open side and a central hub 8 for receiving a conventional roll 9 of pressure-sensitive adhesive tape 10. The leading edge of such roll of tape is passed through an opening 11 of the dispenser body and then over the standard or hump 12 of the dispenser body, where it rests upon the spring knife mechanism and movable support, whereby any desired length of the tape is adapted to be severed and dispensed as hereinafter described.

The standard or hump 12 of the dispenser body is so configured that the upper portion thereof constitutes a cam surface 13 upon which rides a transversely extending cradle 14 having a rounded upper surface 15, two upwardly extending ears 16, and a slot 17 through which extends a knife 18 secured to the body of the dispenser by screw 19. The knife 18 has its upper edge serrated as shown at 20. The upper portion 21 of the knife is wider than its depending body portion, so that it extends throughout the inner surface of the cradle 14 formed by the turned up forward edge of such cradle with the vertical portion thereof extending between such turned up forward edge and the rounded upper surface of the cradle structure.

The cradle structure thus constitutes a movable support for the tape and is permitted to ride upwardly and downwardly upon the cam surface 13 of the standard 12 of the dispenser body as hereinafter described.

The operation of any novel tape dispenser is as follows:

The leading edge 10 of the tape is grasped by the fingers and the desired length of the material which is to be dispensed is unwound from the roll 9 of the tape. Upon a slight pressure downwardly of the leading edge of the tape 10, the transversely extending cradle 14, upon the rounded upper surface 15 of which the tape is positioned, will be depressed a sufficient extent to ride along the cam surface 13, causing the spring knife 18 to be flexed to a slight degree about the screw 19 as its pivot. The serrated cutting edge 20 of the blade is then effective to sever the desired length of tape. As the severed length of tape is removed from the dispenser, the knife blade springs back to its original vertical position by the riding of the cradle structure 14 upwardly along the cam surface 13, retaining the leading edge of the tape in its position upon the rounded surface 15 of the cradle and in position to be grasped by the fingers at its leading edge along the serrated knife blade.

I claim:

In a device for dispensing pressure-sensitive adhesive tape, a support for a roll of tape, a frame 60 in which said roll of tape is rotatably mounted

upon said support, a standard formed on said frame spaced from said roll of tape and having a cam surface at the upper extremity thereof, a spring knife structure secured to the front surface of said standard and extending upwardly beyond said cam surface, and a cradle structure constituting a movable support for the tape extending from said roll over the cutting edge of the spring knife structure, whereby the knife is flexed forwardly of the cam surface while the 10 tape is being severed by the cutting edge.

EDWIN W. MASON.
